CLYDE R. JEFFORDS, OF NEW YORK, N. Y.

SHOE-LACE TIP.

1,115,204.

Specification of Letters Patent. Patented Oct. 27, 1914.

Application filed July 24, 1913. Serial No. 780,925.

To all whom it may concern:

Be it known that I, CLYDE R. JEFFORDS, a citizen of the United States, and a resident of the city of New York, Jamaica, 5 borough of Queens, in the county of Queens and State of New York, have invented a new and Improved Shoe-Lace Tip, of which the following is a full, clear, and exact description.

10 This invention relates to lacings for boots, shoes, leggings and the like, and relates more particularly to a lacing tip and the method of making the same.

The general objects of the invention are 15 to provide an improved tip for shoe and other lacings which is of comparatively simple and inexpensive construction, is more firmly attached to the lacing than other tips of the same class, and which has the 20 additional function of serving as a fastening or attaching device for the free end of the lacing.

More specifically the object of the invention is the provision of a combined tip and 25 fastener for lacings of that type which have only one end free and the other end anchored or attached to the shoe, the said combined tip and attaching device consisting of a piece of sheet metal which is applied to the lacing by being folded with 30 the latter and by offsetting an intermediate portion of the device by imparting a double bend thereto for the double purpose of increasing the hold of the metal on the lacing and for dividing the device into a bill 35 or terminal portion, a grip or base portion and an intermediate shoulder, whereby the combined tip and fastener can be engaged with an eyelet of the shoe by inserting the bill into the eyelet to a position where the bill lies parallel with and against the inner surface of the shoe vamp while the base or grip portion lies parallel with the outer surface of the shoe vamp, with the shoulder 40 engaged with the eyelet so that a pull longitudinally on the lacing maintains the tip and attaching device firmly engaged with the eyelet without the necessity of tying the lacing into a bow, as is now necessary 45 with the common long lacings in use.

For a more detailed understanding of the invention reference is to be had to the accompanying drawing taken in connection with the following description and appended claims.

In the accompanying drawing which

illustrates one embodiment of the invention and wherein similar reference characters are employed to designate corresponding parts throughout the several views, 60 Figure 1 designates a view of a shoe with the improved lacing applied thereto; Fig. 2 is a perspective view of the terminal portions of the lacing, showing the combined tip and attaching devices at one end and 65 the anchoring device or button at the opposite end; Fig. 3 is a plan view of the metal blank for making double tips and attaching devices; Fig. 4 is a plan view showing the lacing placed on the blank; Fig. 5 is a 70 view showing the first bending operation of the blank; Fig. 6 is a view showing the blank and lace folded longitudinally together; Fig. 7 is a side view showing the offsetting of the folded blank; Fig. 8 is a 75 similar view showing the blank cut in two to form the combined tip and attaching device for two lacings; Fig. 9 is an enlarged sectional view of the combined tip and attaching device; and Fig. 10 is a sectional 80 view of an eyelet, showing the combined tip and attaching device interlocked therewith.

Referring to the drawing, A designates a shoe having the usual eyelets 1 for receiving the lacing B, which latter may be a woven or braided fabric, a strip of leather or the like. This lacing B is of such length as to be laced successively through the eyelets of the shoe with one end fastened at 90 the lower eyelet a and the other end fastened to the upper eyelet a'; that is to say, the lacing has only one end free or detachable for the lacing and unlacing of the shoe. As shown in Fig. 2, the lower end of 95 the lacing is provided with a stop or button 2 which is in the form of a disk having an opening 3 through which the lacing passes, there being a serrated tongue 4 or equivalent device on the disk for engaging 100 the lacing and preventing slipping thereof. This attaching device 2 is concealed under the eyelet a and is too large to pass through the eyelet, so that the lower end of the lacing will be effectively fastened to the shoe. 105

The combined attaching device and tip 5 is applied to the upper end of the lacing, such device 5 being a piece of metal suitably bent or folded on the lacing, and this fastening or tip device 5 comprises a bill or 110 terminal portion 6, a shoulder 7 and a base or finger-hold portion 8. The bill portion

2
6 and shoulder 7 are engaged in the upper eyelet α' of the shoe, the bill 6 lying under the eyelet, the shoulder 7 extending through the eyelet and the base portion 8 lying out-
5 side of the eyelet and projecting in a direction opposite from the bill. By this means the longitudinal strain on the upper portion 10 of the lacing will maintain the tip and attaching device 5 firmly engaged with the eyelet α' . The anchoring device 2 at the lower end of the lacing is of course properly adjusted when the lacing is applied to the shoe, so that the lacing throughout its 15 length will be under the required tension when the tip and attaching device 5 is engaged in the eyelet α' . In Fig. 10 the manner of engaging the eyelet α' is clearly shown, and to disengage the device 5 the handle or grip portion 8 thereof is raised 20 so as to bring the bill portion 6 in such a position as to easily slip out of the eyelet.

The manner of applying the combined tip and attaching device to a lacing, especially a braided lacing, is clearly shown in 25 Figs. 3 to 8 inclusive. A brass or other sheet metal blank 10 is employed, of such length as to make two tips and attaching devices 5 and of such width as to be folded or doubled twice. The blank 10 is in the 30 course of application to the lacing folded on the longitudinal lines 11, 12 and 13, Fig. 3. A strip of lacing braid 14 is placed on the blank as shown in Fig. 4 and marginal portions 15 and 16 of the blank are turned 35 upwardly on the lines 11 and 13 and lapped over the lacing braid or strip 14, as shown in Fig. 5. The next step is to double the blank again approximately on the line 12, whereby the lacing braid 14 is also doubled. 40 By this doubling the metal piece and lacing braid are tightly clamped together and a stiff tip will result when the metal is cut transversely at the center, so as to form tips for two laces. Before, however, the folded 45 metal piece is cut the central portion is offset as shown in Fig. 7, and at the same time or as a succeeding step the metal piece is cut in two, as shown in Fig. 8. In the off-setting operation shown in Fig. 7 the folded 50 metal piece is more tightly clamped to the

lacing braid, so that it is practically impossible to pull the metal tip off the lacing. To increase the hold, however, the metal tip can be provided with a series of indentations 55 17, Fig. 9, which indentations bite into the 55 lacing fabric.

From the foregoing it will be evident that the process of applying the tips and attaching devices to the lacing braid from which the lacings are made is easily and inexpensively accomplished, and in the process of forming the tip device for service as attaching means the metallic piece constituting the tip is more firmly anchored to the fabric than would be the case if the tip were 65 straight instead of being offset or provided with the eye-engaging shoulder.

Having thus described my invention, I claim as new and desire to secure by Letters Patent:

1. A lacing provided with a hollow metallic device forming a tip and attaching device, said device being provided with a double bend intermediate its ends to clamp the device to the lacing and to form a base 75 and a bill connected by a shoulder, said bill and base extending in opposite directions from the shoulder.

2. A lacing provided with a combined tip and attaching device consisting of a plate 80 folded around the lacing and offset intermediate its ends to form a shoulder, and a bill extending in one direction from the shoulder, and a base extending in the opposite site direction.

3. A lacing provided with a combined tip and attaching device, said device consisting of a plate having its edges lapped over the lacing and centrally doubled longitudinally with the lacing and offset intermediate its 90 length to form a shoulder, and a bill and base extending in opposite directions from the shoulder.

In testimony whereof I have signed my name to this specification in the presence of 95 two subscribing witnesses.

CLYDE R. JEFFORDS.
